BURNER CONTROL APPARATUS WITH
COMPONENT CHECKING MEANSJohn M. Wilson, Minneapolis, Minn., assignor to
Minneapolis-Honeywell Regulator Company,
Minneapolis, Minn., a corporation of Delaware

Application June 27, 1949, Serial No. 101,507

18 Claims. (Cl. 158—123)

1

The present invention relates to burner control apparatus and particularly to that type of burner control apparatus employing condenser timing for obtaining safety shutdown and proper sequencing of the burner control. This application is a continuation in part of an application filed by the present inventor for "Burner Control Apparatus," on March 10, 1948, Serial No. 13,981, now abandoned.

In some present day burner installations, particularly those employing gas as a fuel, it is desirable to have almost immediate shutdown in the event, that upon initiation of operation, combustion is not established or upon the occurrence of a flame failure. This may be accomplished by using an electronic flame detector to regulate the charging time of a condenser through resistor. When the condenser is charged sufficiently, the charge may be used to bias an electron discharge device out of conduction to render the apparatus inoperative. When combustion is detected by the electronic flame detector the charging circuit of the condenser is rendered ineffective.

By using an electronic flame detector in the present invention it is possible to shut the burner down the instant it is determined combustion is not present. The electronic flame detector that has been employed responds almost instantly to the presence or absence of flame. As the flame detector employs an electron discharge device which is subject to failure, it is necessary to provide a control apparatus which will be quickly rendered inoperative upon the flame failure and which will check the circuit components in the event that the flame detector should be inoperative or should be operating falsely.

It is therefore an object of the present invention to provide a burner control apparatus of the electronic type which will quickly respond to the presence or absence of flame and which will be maintained inoperative in the event there is a component failure in the control apparatus.

Another object of the present invention is to provide a burner control apparatus which employs resistor-condenser timing to accomplish shutdown of a burner when there is a flame failure and which checks the components of the control apparatus to maintain the burner inoperative when there is a false indication of flame.

Still another object of the present invention is to provide a control apparatus employing an electron discharge device which is rendered operative upon the need for operation of a burner

and inoperative upon the occurrence of a flame failure by a biasing voltage charging a condenser associated with the discharge device and further biasing the discharge device to be maintained inoperative when a flame detection device falsely indicates flame.

A further object of the present invention is to provide a burner control apparatus employing an electron discharge device which is rendered operative upon the need for operation of a burner and an electronic flame detector which will render the discharge device inoperative when there is a flame failure and maintain the discharge device inoperative when there is a false indication of flame.

A still further object of the present invention is to provide a burner control apparatus employing an electron discharge device which is biased to be inoperative upon a flame failure by one biasing circuit and to be biased to be inoperative by a second circuit when there is a false indication of flame and where the latter biasing circuit will be maintained continuously until the fault causing the false indication of flame is removed.

These and other more detailed and specific objects will be disclosed in the course of the following specification, reference being had to the accompanying drawings of which:

Figure 1 shows in detail one embodiment of the invention as applied to a gas burner control, and

Figure 2 shows the invention in slightly modified form.

Referring to Figure 1, the numeral 10 represents a gas burner which is adapted to be supplied fuel through a conduit 11. Controlling the flow of fuel through the conduit 11 is a valve 12 which is electrically operated. The fuel of the burner is ignited by a pair of ignition electrodes 13 and 14 which are operatively energized by an ignition transformer 15 consisting of a primary winding 16, energized from a common source of power, and a secondary winding 17. An electric spark between the ignition electrodes will ignite the gas flowing from a pilot nozzle 18. Supplying fuel to the pilot nozzle 18 is a conduit 19 which has controlling the flow of fuel therein, a further electrically operated valve 20. Both valves 12 and 20 are of the type which are maintained open as long as energized and moved to closed position upon deenergization.

To indicate the need for operation of the burner 10, a thermostat 21 has been provided which may be seen to consist of a bimetal 22

which is operable upon the temperature falling and rising to move a switch blade 23 into and out of engagement respectively with an associated switch contact 24. Located within a housing 37, indicated by dotted lines, are the control circuits for actuating the valves 12 and 20 and ignition transformer 15 upon the demand for heat as indicated by thermostat 21. Energized by the actuation of the thermostat 21 is a control relay 120 having a relay winding 121 which is operable when energized to move an associated switch blade 122 from engagement with a switch contact 123 into engagement with a further contact 124. Energized by the control relay 120 is a main control electron discharge device 25 in the form of a triode having an anode 26, a control electrode 27, and a cathode 28. Energized by the current flow through the triode 25 is a relay 29 which may be seen to consist of a relay winding 30, adapted to move a pair of switch blades 31 and 32 which are normally biased so that the switch blade 31 engages a contact 33 and the switch blade 32 is biased out of engagement with the contact 34. When relay 30 is energized, the switch blades 31 and 32 engage contacts 35 and 34 respectively. A condenser 36 is connected across the relay winding 30 to function in a normal manner to by-pass the alternating current flowing in the energizing circuit for triode 25. Connected between the control electrode 27 and cathode 28 of discharge device 25 is a timing condenser 39. Associated with the condenser 39 is a reset switch 40 and a switch contact 41, the latter of which is tapped to a time delay resistor 42 at 43.

Supplying power to an electronic flame detector is a transformer 45 having a primary winding 46 connected to a common source of power and a secondary winding 47 having taps 48 and 49. Energized by the transformer 45 is an electron discharge device 50 in the form of a triode having an anode 51, a control electrode 52, and a cathode 53. Also energized by the transformer 45 is a further electron discharge device 54 in the form of a triode having an anode 55, a control electrode 56, and a cathode 57. Associated with the input of triode 50 is a biasing condenser 58, a filter network consisting of a resistor 59 and condenser 60, and a biasing resistor 61. Associated with the input of triode 54 are a pair of resistors 62 and 63. The output circuit of the triode 54 includes a relay 65 having a relay winding 66 which is adapted to move a pair of switch blades 67 and 68. The switch blades 67 and 68 are normally biased so that the switch blade 67 engages a switch contact 69 and the switch blade 68 is biased out of engagement with an associated contact 70. When the relay is energized the switch blade 67 moves into engagement with an associated contact 71 and the switch blade 68 moves into engagement with the associated contact 70. A condenser 72 is provided to by-pass the alternating current around the relay winding 66. Also associated with the flame detection portion of the control apparatus is an electrode 75 which is positioned in a manner to intersect the flame from either the pilot nozzle 18 or the burner 10.

Normal operation of Figure 1

In considering the normal operation of the subject control apparatus it will be assumed that all of the components are in the position shown upon the drawing such that there is no demand for operation of the burner and neither the main control relays 120 and 29 nor the flame detection

relay are energized. Under these conditions the ignition transformer will not be energized, the pilot valve 20 will not be energized and the main control valve 12 will not be energized. The thermostat 21 is used to indicate the need for operation of the burner 10 and upon such need the bimetal 22 will move the switch blade 23 into engagement with its associated contact 24. With blade 23 engaging switch contact 24 an energizing circuit is completed to the control relay 120 from the input power line 89 through conductors 81 and 82, contact 24, blade 23, bimetal 22, conductor 83, relay winding 121, and conductors 86 and 87 to the other input power line 88. When this relay becomes energized, the switch blade 122 will move into engagement with contact 124 to complete an energizing circuit to the main control triode 25. This circuit to triode 25 may be traced from the input power line 88 through conductors 87, 85, and 84, relay winding 30, anode 26, cathode 28, conductor 125, switch blade 122, switch contact 124, and conductors 126 and 81 back to the other input power line 89. It will be noted that this last traced circuit includes the relay winding 30. In the absence of any biasing voltage on the input of the triode 25 the resultant current flow will cause relay winding 30 to move the switch blades 31 and 32 into engagement with their associated switch contacts 35 and 34 respectively.

When switch blade 32 engages switch contact 34 an energizing circuit is completed to the ignition transformer 15 and the pilot valve 20. This circuit may be traced from the input power line 88 through conductors 87, 85 and 89, switch blade 32, switch contact 34, conductors 90 and 91, switch blade 67, switch contact 69, conductor 92, ignition transformer primary winding 16, and conductors 93 and 94 back to the other input power line 89. The energizing circuit to the pilot valve 20 is almost identical to the last traced circuit except relay 65 and this circuit may be traced from the input power line 88 through conductors 87, 85 and 89, switch contact 32, switch contact 34, conductors 90 and 95, pilot valve 20, and conductors 93 and 94 to the other input power line 89. With pilot valve 20 and ignition transformer 15 energized, fuel will pass through the conduit 19 to the pilot nozzle 18 where the spark across the ignition electrodes 13 and 14 will ignite the fuel.

The flame detector employed in the subject control apparatus is of the type that is adapted to utilize the rectifying characteristics of a flame bridging a pair of flame electrodes. It is a well known phenomenon that when a pair of flame electrodes are positioned in the path of a flame and voltage is applied to those electrodes there will be a current flow through the flame. The current flow through the flame will be greater in one direction than it is in the other, the direction of greatest electron conductivity being in the direction of propagation of the flame. Just how this is utilized in the present control apparatus will be understood from the discussion of the flame detector which follows.

The flame electrode circuit is used to bias triode 50 into and out of conduction in accordance with the presence or absence of flame that may be existing between the pilot nozzle 18 and the flame electrode 75. The flame detection circuit may be traced from the lower terminal of secondary 47 through conductors 101 and 100, ground 99, ground 98, pilot nozzle 18, electrode 75, conductor 97, condenser 58 and conductor 96 to the tap 48.

of the secondary 47. As there is alternating current on the secondary 47 there will be alternating current applied across the gap between the flame electrode 75 and the pilot nozzle 18 which will mean that there will be a unidirectional component of current flow through the last traced circuit which will tend to charge the condenser 58 to a predetermined voltage of a polarity which will be negative on the lower terminal and positive on the upper terminal. The condenser 58 will be so charged during the half cycle of the alternating power supply when the tap 48 is positive with respect to the lower terminal of secondary 47. On the following half cycle, the condenser 58 will discharge in a circuit that may be traced from the lower terminal of condenser 58 through resistors 59 and 61, conductor 101, secondary 47, tap 48 and conductor 96 to the upper terminal of condenser 58. The current flow through resistor 61 will result in condenser 60 assuming a charge which will be negative on the upper terminal and positive on the lower terminal. The resistor 59 and the condenser 60 form a filter network which serves to smooth out any flame fluctuation occurring at the flame electrode 75 and changes in the charging rate of condenser 58. With condenser 60 being effectively charged by the charge on the condenser 58 the triode 50 will be biased to be nonconductive since the condenser 60 is connected directly between the control electrode 52 and the cathode 53. When triode 50 is nonconducting the triode 54 will be biased into conduction and will energize relay 65 in a manner to be explained hereinafter. The energizing circuit for the triode 54 may be traced from the upper terminal of the secondary 47 through conductor 106, relay winding 66, conductor 107, anode 55, cathode 51, and conductors 108, 103 and 102, back to the tap 48 of the secondary 47. The triode 54 will be conducting since the control electrode 56 is connected to a voltage divider consisting of resistors 62 and 63 connected across the upper half of the secondary 47, and is biased to be conductive since the control electrode will be positive with respect to the cathode on the conducting half cycle of the power source.

When the relay 65 becomes energized the relay winding 66 will move the switch blades 67 and 68 into engagement with their associated switch contacts 71 and 70 respectively. When the switch blade 67 engages switch contact 71 and opens the switch contact 69 the ignition circuit to transformer 15 is deenergized as the energizing circuit for the transformer 15 was completed through switch blade 67 and switch contact 69, and the main control valve 12 will be energized by switch blade 67 engaging switch contact 71. This energizing circuit may be traced from the input power line 88 through conductors 87, 85 and 89, switch blade 32, switch contact 34, conductors 90 and 91, switch blade 67, switch contact 71, conductor 109, main control valve 12, and conductors 110 and 94 back to the other input power line 80. The system is now operating normally with pilot valve 20 energized and the main control valve 12 energized.

As soon as the burner 10 has operated for a sufficient length of time the thermostat 21 will no longer indicate a need for operation of the burner so that the switch blade 23 will be moved out of engagement with the associated switch contact 24 by bimetal 22. This will open the energizing circuit to the control relay 120 so that the switch blade 122 will move from engagement with contact 124 into engagement with contact

123. When blade 122 moves from engagement with contact 124, the energizing circuit to the main control tube 25 is opened and the relay 29 will become deenergized. When the blade 122 engages contact 123, the control electrode 27 of device 25 is connected to the cathode 28 by a circuit that may be traced from control electrode 27, through conductor 130, switch contact 123, switch blade 122 and conductor 125 to cathode 28. This circuit is provided to insure that the control electrode will be at the same potential as the cathode upon a subsequent demand for burner operation, as indicated by the reoperation of the thermostat 21. When relay 29 becomes deenergized, the switch blades 31 and 32 will move to their deenergized positions so that the switch blade 32 will be no longer engaging switch contact 34 and the energizing circuit to the pilot valve 20 and the main control valve 12 will be broken and the fuel supply to the burner 10 will be discontinued. With fuel no longer supplied to the pilot nozzle 18 there will be no flame emitting from the nozzle to intersect the flame electrode 75. With no rectifying action taking place in the flame electrode circuit the condenser 58 will not be charged to bias the triode 50 to be nonconducting. With triode 50 conducting its energizing circuit may be traced from the secondary 47 at tap 48 through conductors 102 and 103, resistor 63, conductors 104 and 105, anode 51, cathode 53, and conductors 100 and 101 back to the lower terminal of the secondary 47. It will be noted that the last traced circuit includes the resistor 63 which will have a voltage drop across it on the conducting half cycle of the triode 50 such that the upper terminal will be negative. This voltage drop is utilized to maintain the triode 54 to be effectively nonconducting when the triode 50 is conducting, since the triode 54 is phased to be conducting on the same half cycle as the triode 50. With both relays 29 and 65 deenergized the control apparatus is in a condition for a further operating cycle.

45 Operation of Figure 1 on flame failure

In the operation discussed so far no consideration has been given to the safety features of the control apparatus. One such feature provides for automatic shutdown in the event that there is a failure of the electrode 75 to detect the presence of flame. Assume that there is a need for operation of the burner and the thermostat 21 is closed so that the switch blade 23 engages switch contact 24 which action completes the energizing circuit to relay 120 and thereby to triode 25. With triode 25 energized the relay 29 will become energized so that the switch blades 31 and 32 will move into engagement with their associated switch contacts 35 and 34 respectively.

As explained above, when switch blade 32 engages switch contact 34 on the starting portion of the operating cycle the ignition transformer 15 is energized as well as the pilot valve 20. Normally fuel would emit from the burner nozzle 13 and the ignition electrodes 13 and 14 would ignite the same. In the event that there was no ignition of the fuel coming from pilot nozzle 18 there would be no flame intersecting the flame electrode 75 and there would be no rectification in the flame detection circuit to charge the condenser 58. With no charge on the condenser 58 the triode 50 will be biased in its conducting range so that there will be a current flow through 75 the resistor 63 which will effectively bias the tri-

ode 54 to be nonconducting so that it will not energize the relay 65.

As noted above, the voltage drop across the resistor 63 is such that its upper terminal is negative and its lower terminal is positive. This voltage drop is utilized in the biasing circuit for the main control triode 25 by reason of its connection to the biasing condenser 39. Inasmuch as it is desired to bias the main control triode 25 below the point necessary to maintain the relay 29 energized when there is no flame present in the burner 10 or the pilot nozzle 18 a biasing circuit must be established between the resistor 63 and the biasing condenser 39. This circuit may be traced from the upper terminal of the condenser 39 through conductor 111, resistor 42, conductors 112 and 104, resistor 63, conductors 103, 113, and 126, switch contact 124, switch blade 122, and conductor 125 back to the lower terminal of the condenser 39. It will be noted that this last traced charging circuit for the condenser 39 includes a resistor 42. The function of this resistor is to delay the charging time of the condenser 39 a predetermined amount. If the condenser 39 is charged sufficiently negative by the voltage across the resistor 63 the control electrode 27 will bias the main control tube 25 below the point necessary to maintain the relay 29 energized and the control system will be rendered inoperative. To put the apparatus back in operation it is necessary to depress the manual reset lever 40 so that it engages switch contact 41. This will effectively short circuit the condenser 39 so that it will discharge and the main control tube 25 will once again become conductive to reenergize the relay 29 and attempt to start the burner in operation again.

It is also possible to put the apparatus back in operation upon a flame failure by manually opening the room thermostat 21 so that the energizing circuit to the control relay 120 is opened. When this relay is deenergized, the condenser 39 will be shorted out by the blade 122 engaging contact 123, and when so shorted out the control electrode 27 will be at the same potential as the cathode 28 so that a subsequent closing of the room thermostat will permit the control tube to conduct until the condenser is again charged sufficiently negative to cut the tube off or a flame is established at the burner.

The flame failure considered so far has been only in connection with the starting cycle. If flame is established prior to the time that the condenser 39 becomes fully charged, the condenser will be effectively shorted out and the control electrode 27 and cathode 28 of the main control tube 25 will be connected directly together so that the control tube will remain conductive. This shunting circuit will occur only when both the main control relay 29 and the flame detection relay 65 are energized so that the switch blade 31 of relay 29 engages switch contact 35 and the switch blade 68 of relay 65 engages switch contact 70. With these two relays energized, a circuit may be traced from the control electrode 27 through conductors 111 and 115, switch blade 68, switch contact 70, conductor 116, switch blade 31, switch contact 35, and conductor 118 back to the cathode 28. This circuit is actually a short circuit connection which connects the control electrode 27 to the cathode 28 and with such a connection triode 25 will continue to conduct and maintain relay 29 energized.

Should the apparatus be operating normally so that there is fuel being supplied to both the

75 pilot nozzle 18 and the burner 10 and there is a subsequent flame failure, the flame detection relay 65 will become deenergized. With the relay 65 becoming deenergized the switch blade 67 5 will engage switch contact 69 so that the energizing circuit to the ignition transformer 15 will once again be completed. The energizing circuit to the main control valve 12 will be broken by the movement of the switch blade 67 out of engagement with its associated switch contact 71 and the shunting circuit for condenser 39, associated with the input of control tube 25, will be opened by the movement of the switch blade 68 out of engagement with its associated switch contact 70. In the event that the reenergization of the ignition transformer 15 fails to establish combustion at the pilot nozzle 18 within a predetermined time the condenser 39 will be charged sufficiently through resistor 42 to bias the triode 25 below the point necessary to maintain relay 29 energized and when this occurs the switch blades 31 and 32 will move out of engagement with their associated contacts 35 and 34 respectively so that the pilot valve 20 and the ignition transformer 15 will be deenergized and the system will be inoperative until such time as the manual reset lever 40 is pushed into engagement with switch contact 41 to once again discharge the condenser 39. With condenser 39 30 discharged by the reset lever actuation the control tube will once again become conductive and attempt to initiate operation of the burner and if combustion fails to take place the condenser 39 will once again be charged to a point where it will bias the control tube 25 to be effectively nonconducting.

Operation of Figure 1 on ground out

As it is possible to have a condition where the 40 flame electrode 75 will be short-circuited with the pilot nozzle 18, which condition is referred to as a ground out condition, it is desirable to see that the control apparatus does not become operative. With the electrode 75 shorted to the pilot nozzle 18 there can be no rectification of the 45 flame detection circuit and therefore the condenser 58 will not be charged so that it will have no biasing effect on the triode 50 which will remain conductive sufficiently to maintain the triode 54 nonconductive as explained above. With the triode 54 effectively nonconductive, the relay 65 will not become energized so that the shunting circuit around the condenser 39 will not be completed and the condenser 39 will be charged by the voltage existing across resistor 63, as explained above, to bias the main control tube 25 below the point necessary to maintain relay 29 energized. When relay 29 becomes deenergized both the ignition transformer 15 and the pilot valve 20 will become deenergized and the system will remain inoperative until such time as the manual reset lever is depressed to discharge the condenser 39.

Operation of Figure 1 upon false indication of flame

As the control apparatus employs an electronic flame detector, it is desirable to employ some means of preventing operation of the control apparatus when that flame detector is falsely indicating flame as might occur should some of the elements within the triodes 50 or 54 become shorted or open circuited in such a manner that the triode 54 remains conductive and the relay 65 energized. This is accomplished in the pres-

ent invention by applying an alternating current bias voltage to the control electrode 27 of the main control tube 25 whenever the relay 65 is energized and there is no demand for operation of the burner or when the relay 29 is deenergized. When the relay 29 is deenergized so that the switch blade 31 engages switch contact 33 and when the relay 65 is energized falsely indicating the presence of flame so that the switch blade 68 is engaging switch contact 70 it is possible to complete the biasing circuit to the control electrode 27 of the main control tube 25. This circuit may be traced from the tap 49 of the secondary 47 through conductor 119, switch contact 33, switch blade 31, conductor 116, switch contact 70, switch blade 68, and conductors 115 and 111 to the control electrode 27. To establish a common potential between the biasing voltage on the control electrode 27 and the voltage on the cathode 28 it is necessary to have the cathode 28 effectively connected to a point on the transformer secondary 47. This is done by direct connection of the cathode 28 through conductor 125, switch blade 122, switch contact 124, and conductors 82, 113, and 182 to the tap 48 of the secondary 47. It will be noted that this last traced circuit is completed only when the thermostat 21 is closed to energize the relay 120 upon a demand for more heat but since the control relay 29 is deenergized when the thermostat is open it will make no difference since the relay will not become energized due to the completion of the last traced biasing circuit. The voltage between the taps 49 and 48 of the secondary 47 are of such phase with respect to the alternating current voltage on the triode 25 that the control electrode 27 will be negative with respect to the cathode 28 on the normally conducting half cycle of the triode 25. This voltage will remain biasing the control electrode 27 until the fault has been removed from the flame detection portion of the control apparatus. With triode 25 so biased, the current flow through the triode will not be sufficient to energize relay 29. It will be impossible to appreciably affect this biasing voltage by depressing the reset lever 46 because of the fact that the resistor 42 is tapped at 43 and there is sufficient resistance in the circuit shunting the control electrode 27 of the cathode 28 when the lever is depressed that the alternating current biasing voltage will not be short-circuited to permit energization of the main control relay 29.

As soon as the fault has been cleared from the flame detection portion of the control apparatus the relay 65 will become deenergized so that the switch blade 68 will move out of engagement with its associated switch contact 70 and the alternating current biasing circuit will be interrupted to thereby permit operation of the control apparatus in the normal manner.

Figure 2

The apparatus shown in Figure 2 accomplishes the same type of control as that of the apparatus shown in Figure 1. In Figure 2, the components which correspond to those of Figure 1 carry the same reference numerals. The circuits in Figure 2 have been slightly modified in the timing circuit and in the component checking circuit.

In Figure 2, the room thermostat 21 is effective to control appropriate electrical circuits within the housing 137, the latter of which initiate and check the operation of the pilot burner 18 and the main burner 10. Located within the housing 137 is a flame detection circuit which corresponds

identically to that of Figure 1 except that a modified relay 165 has been added in the output circuit of the discharge device 54. This relay comprises a relay winding 166, a plurality of switch blades 167, 168, 169 and 170. The switch blade 167 is normally biased by means not shown into engagement with an associated switch contact 172. When the relay is energized the switch blade moves into engagement with a contact 171. Switch blade 168 is normally biased out of engagement with an associated contact 173 and switch blade 169 is normally biased out of engagement with a contact 174. Switch blade 170 is normally biased into engagement with a contact 175. Supplying power to the flame detection circuit is a transformer 145 having a primary winding 146 and a pair of secondary windings 147 and 148. The secondary winding 147 is tapped at 149. The secondary 148 is used to supply the filament voltages for the discharge devices of the flame detector and for the main control tube 25. This transformer is also used for alternating current biasing purposes in a manner which will be understood when the operation of the present figure is considered.

The operation of the flame detector shown in Figure 2 is the same as that of the flame detector shown in Figure 1 and the output control relay 165 will be energized when a flame is detected and will be deenergized when there is no flame or there is faulty operation at the flame rod 75.

A control relay 129 has been added to the output circuit of the main control tube 25 and this relay comprises a relay winding 130, and a plurality of switch blades 131, 132 and 233. The switch blades are normally biased out of engagement with associated contacts 134, 135 and 136 and the blade 132 is biased into engagement with an associated contact 137.

An additional control relay 150 is associated with the timing circuit on the input of the main control tube 25. This control relay comprises a relay winding 151, a plurality of switch blades 152, 153 and 154 which are normally biased out of engagement with their associated switch contacts 155, 156 and 157. Associated with the relay 150 is a current limiting resistor 160.

Associated with the input of the main control tube 25 is a timing condenser 161, a timing resistor 162 and a grid lead resistor 163. A pair of filament heaters 164 are connected to the secondary winding 148 and are utilized for heating the cathodes of triodes 25, 50, and 54.

Operation of Figure 2

In considering the operation of Figure 2, it will be noted that the apparatus as shown upon the drawing is in the deenergized position with the room thermostat not calling for burner operation and the control relays all deenergized. Also deenergized are the ignition device, the pilot valve and the main valve. When there is a need for burner operation the room thermostat 21 will close and will complete an energizing circuit to the main control tube 25. This energizing circuit may be traced from the lower terminal of secondary 147 through conductors 180 and 181, relay winding 130, conductor 182, anode 26, cathode 28, conductors 183, 226 and 184, bimetal 22, switch blade 23, switch contact 24, and conductors 185 and 186 to tap 149 on secondary 147. With this last traced energizing circuit complete, the current flow therethrough will be sufficient to energize the control

relay 129 so that the switch blades 131, 132 and 133 will move into engagement with their associated contacts 134, 135 and 136, respectively.

When switch blade 133 engages contact 136, an energizing circuit is completed through the ignition transformer 15 and the pilot valve 20. This energizing circuit may be traced from the input power line 80 through conductors 190, 191, and 192, switch contact 136, switch blade 133, conductor 193, switch contact 175, switch blade 170, conductor 194, primary 16 of ignition transformer 15, and conductors 195 and 196 back to the other input power line 88.

The energizing circuit for the pilot valve 20 is almost identical to the above traced circuit except that the circuit does not include any contacts of the flame indicating relay 165. This circuit may be traced from the upper input power line 80 through conductors 199, 191 and 192, switch contact 136, switch blade 133, conductors 193 and 197, pilot valve 20, and conductors 195 and 196 to the lower input power line 88.

Also energized upon the energization of the control relay 129 is the control relay 150. The energizing circuit for this relay may be traced from the input power line 80 through conductors 190 and 191, switch contact 134, switch blade 131, conductors 200, switch contact 172, switch blade 167, conductor 201, conductor 203, relay winding 151, and conductors 204 and 205 to the other input power line 88. When relay 150 becomes energized a holding circuit therefor is completed which is independent of the relay contacts of either relays 129 and 165 and this holding circuit may be traced from the input power line 88 through conductors 190 and 202, switch blade 152, switch contact 155, resistor 160, conductor 203, relay winding 151, and conductors 204 and 205 to the other input power line 88. The further circuit completed by the energization of the relay 150 is a charging circuit for the timing condenser 161. It will be recalled that in considering the operation of the flame indicator in Figure 1, there was a voltage drop across the load resistor 63 such that the upper terminal of the resistor was negative and the lower terminal was positive when the triode 50 is on the conducting half cycle of the power supply. With a condenser 64 connected in parallel with the resistor 63, the polarity across the resistor 63 will then be maintained there by the fact that on the half cycles in which the tube 50 is not conducting, the condenser 64 will be discharging through the resistor 63 and will be maintaining the polarity thereon. This charging circuit may be traced from the lower terminal of resistor 63 through conductors 210 and 185, switch contact 24, switch blade 23, bimetal 22, conductor 184, condenser 161, conductor 211, switch contact 156, switch blade 153, conductor 212, switch blade 154, switch contact 157, timing resistor 162, and conductor 213 back to the upper terminal of resistor 63. This charging circuit, when completed, will start charging the timing condenser 161 so that its upper terminal will be negative with respect to its lower terminal.

If a flame is established at the pilot nozzle 18, the presence of the pilot flame will be detected by the flame rod assembly 75 and will be indicated by the operation of the relay 165. When this flame indicating relay becomes energized the switch blades 167, 168, 169 and 170 will all move to the energized position where the blade 167 will engage switch contact 171, blade 168 will engage contact 173 and blade 169 will engage contact

174. The blade 170 will move out of engagement with contact 175. When blade 169 engages contact 174 the control electrode 27 is connected directly to the cathode 28 of the main control tube 25 so that any charge upon the timing condenser 161 will have no effect upon the operation of the control tube. This shorting circuit may be traced from the control electrode 27 through conductors 215 and 216, switch blade 169, switch contact 174, conductor 217, switch blade 132, switch contact 135, conductor 218 to cathode 28. With this shorting circuit complete, the control tube will stay conducting and will maintain the control relay 129 energized.

When the flame indicating relay 165 becomes energized the energizing circuit to the ignition transformer 15 is broken by the movement of switch blade 170 out of engagement with its contact 175. Inasmuch as the pilot valve is energized independently of this last switch contact, the pilot valve will remain energized. When the switch blade 168 engages contact 173, an energizing circuit is completed to the main valve 12 and this energizing circuit may be traced from the input power line 80 through conductors 199, 191 and 192, switch contact 136, switch blade 133, conductors 193 and 222, switch contact 173, switch blade 168, conductor 222, main valve 12, and conductors 223 and 196 back to the other input power line 88. When the switch blade 167 engages contact 171, a short circuit is completed across the relay winding 151 so that the relay 150 will become de-energized. This shorting circuit may be traced from the input power line 88 through conductors 285 and 225, switch contact 171, switch blade 167, conductor 201, conductor 293, relay winding 151 and conductor 204 back to conductor 205. When relay 150 becomes deenergized, the switch blades will move out of engagement with their associated contacts and the charging circuit for the timing condenser 161 will be opened and the holding circuit for the relay itself will be opened.

The apparatus is now operating normally with the main control relay 129 energized, the flame indicating relay 165 energized and the control relay 150 deenergized. Further, the ignition transformer is deenergized and the main pilot valve and main valve are energized.

As soon as the thermostat 21 no longer indicates the need for burner operation, the switch blade 133 will move out of engagement with contact 24 and this will open the energizing circuit to the main control tube 25. With the control tube 25 deenergized, the main control relay 129 will become deenergized. When the control relay 129 becomes deenergized the switch blade 133 will move out of engagement with contact 136 to open the energizing circuit through the main valve 12 and the pilot valve 20 so that the burner assembly will be shut down. When flame is no longer detected by the flame rod 75, the flame indicating relay 165 will become deenergized. When this occurs, the apparatus will be completely shut down and will be ready for another operating cycle upon a further demand for burner operation as indicated by the operation of the room thermostat 21.

Operation of Figure 2 on flame failure

If the operating cycle is started in a normal manner by the room thermostat first closing to indicate a need for burner operation, the control relay 129 and the control relay 150 will become energized, in the manner described above. When the relay 129 becomes energized the pilot valve

20 and the ignition transformer 15 will be energized to attempt to establish a flame at the pilot nozzle 18. When the relay 150 becomes energized the charging circuit to the timing condenser 161 is completed from the load resistor 63. If no flame is detected by the flame rod 75, the flame indicating relay 165 will remain in the deenergized position and the charging circuit to condenser 161 will not be interrupted. This will mean that after a predetermined time, a time dependent upon the size of the timing resistor 162 and the timing condenser 161, the condenser 161 will assume a charge which is negative on the upper terminal and positive on the lower terminal and of sufficient magnitude to bias the main control tube 25 below the conducting point necessary to maintain the control relay 129 energized. When the relay 129 becomes deenergized the ignition transformer and the pilot valve will be deenergized. Inasmuch as the control relay 150 establishes a holding circuit for itself, independent of any contact with either relay 129 or 165, this relay will remain energized and when so energized the charging circuit to the timing condenser 161 will remain intact and will maintain the bias on the control group 25 below the point necessary to pull in the control relay 129. The apparatus will stay in this condition until such time as the reset button is actuated so that the switch blade 40 moves into engagement with contact 41. When this occurs, the condenser 161 will be shorted out by a circuit that may be traced from the upper terminal of condenser 161 through conductor 211, switch contact 156, switch blade 153, conductor 212, switch blade 154, switch contact 157, switch contact 41, switch blade 40, and conductor 226 to the lower terminal of condenser 161.

When the condenser 161 has been discharged, it is possible to reenergize the main control relay 129 since the control electrode 27 will have the same potential as the cathode 28 and the current flow through relay 25 should be sufficient to energize the main control relay 129. This will mean that a further attempt will be made to establish flame at the pilot nozzle 18. If flame is established, the operation of the apparatus will be as explained above, and the flame will be indicated by the operation of the flame indicating relay 165 which in turn will energize the main valve 12 so that the apparatus will be operating normally.

In the event that the apparatus should be operating normally and there should be a subsequent flame failure so that the flame indicating relay 165 became deenergized, it is also desired that the apparatus be rendered inoperative and the control valve be deenergized. It will be noted that as soon as the flame indicating relay 165 becomes deenergized, with the room thermostat 21 still calling for operation of the burner, the short circuit around the relay winding 151 will be removed and the relay will become energized. When the relay does become energized the charging circuit for the timing condenser 161 is completed and, after a predetermined time, the condenser will charge and will bias the control tube 25 to a point where its conductivity will no longer maintain the control relay 129 energized. When the relay 129 becomes deenergized the energizing circuit to the main valve and pilot valve will be deenergized and the burner apparatus will be completely shut down. In order to put the apparatus back in operation it is necessary that the reset switch

40 be actuated to discharge the timing condenser 161 and when this occurs, a further attempt will be made to establish burner operation and if this fails, the apparatus will again be shut down.

5 *Operation of Figure 2 upon false indication of flame*

In the event that there is a false indication of flame as would occur if the flame indicating relay 165 were to remain in the energized position after the burner has been shut down by the opening of the room thermostat 21, it is desired that there be no further operation of the control apparatus until the fault causing operation of the flame indicating relay is removed. The maintaining of the apparatus inoperative is accomplished in somewhat the same manner as was accomplished in the apparatus shown in Figure 1. In the present figure, when there is a false indication of flame, an alternating current bias is obtained from the secondary winding supplying energizing voltages for the filaments 164. This alternating bias from filament secondary 148 is applied between the control electrode 27 and cathode 28. The circuit from the secondary 148 may be traced from the upper terminal of the secondary through conductor 230, switch contact 137, switch blade 132, conductor 217, contact 174, switch blade 169, and conductors 216 and 215 to the control electrode 27. The connection of the secondary 148 to the cathode may be traced from the lower terminal of secondary 148 to conductor 231, conductor 186, conductor 185, switch contact 24, switch blade 23, and conductors 184, 226 and 183 to cathode 28. It will be noted that this last traced circuit is completed only upon the closing of the room thermostat 21. This will be of no significance inasmuch as soon as the biasing circuit is completed, a negatively phased alternating current bias is supplied between the control electrode 27, cathode 28, such that the control electrode 27 will be negative with respect to the cathode 28 on the half cycle when the anode 26 is positive with respect to the cathode, or on the normally conducting half cycles.

45 With the control electrode biased negatively with respect to the cathode on the conducting half cycle of the tube, the current flow will not be sufficient to energize the control relay 29 and the apparatus will stay in a shutdown position until the fault causing false operation of the relay 165 is removed. As in Figure 1, the depressing of the reset switch will have no effect upon the operation upon a component failure. This will be understood when it is noted that 50 the relay 150 will be deenergized with relay 165 operating due to the short circuit around the relay. With relay 150 deenergized, it is impossible to complete a shorting circuit between the cathode 28 and control electrode 27 by the depressing of the reset switch 40.

Conclusion

From the foregoing it can be seen that I have provided a burner control apparatus which is operative to shut the burner down upon a flame failure, to provide against ground out conditions of the flame detection circuit, and to maintain the control apparatus inoperative when there is a false indication of flame by the flame detection relay. Further it may be seen that I have provided a control apparatus which employs condenser timing for establishing the safety shutdown of the control apparatus and providing with that feature a fail safe circuit which 75 can be rendered ineffective upon a flame failure

or can be maintained effective continuously upon a false indication of flame.

Although I have described my invention in connection with a gas burner control, and while it is particularly well adapted for use there, it will be obvious to those skilled in the art that my invention could be applied to any burner control apparatus where it is desired to use an electron discharge device and a condenser timed input safety biasing circuit. Therefore, I intend to be limited solely by the scope of the appended claims in which I claim:

1. Apparatus for controlling a fuel burner having a control means for indicating the need for burner operation comprising in combination, an electron discharge device adapted to be energized by the control means, relay means, said relay means having switch contacts adapted to energize means for initiating operation of the burner, means connecting said relay means in the energizing circuit of said discharge device, biasing means, a source of biasing potential, time delay means, means connecting said biasing means, said time delay means and said source of biasing potential in biasing relation to said discharge device so that said discharge device will be rendered inoperative after a predetermined time delay, electric switching means adapted to be actuated by means indicating proper burner operation, means including said electric switching means for rendering said biasing means ineffective when said electric switching means is actuated and indicating the presence of combustion, additional biasing means, and means including said electric switching means connecting said additional biasing means to said discharge device when said electric switching means is in actuated position and indicating the presence of combustion and there is no demand for operation of the burner to maintain said discharge device inoperative upon a subsequent demand for burner operation.

2. Apparatus for controlling a fuel burner having a control means for indicating the need for burner operation, comprising in combination, an electron discharge device having input and output terminals, a source of power, an electric circuit adapted to be completed by the control means for connecting said discharge device to said source of power, a relay, means connecting said relay to the output terminals of said discharge device so that said relay is energized when the current flow in said discharge device is greater than a predetermined value, means actuated by said relay for initiating operation of a burner when said relay is energized, a condenser, means connecting said condenser in biasing relation to the input terminals of said discharge device, a charging circuit connected to said condenser by means including the control means for charging said condenser after a predetermined time delay to a potential which will bias said discharge device below the point necessary to maintain said relay energized, electric means adapted to be energized by means indicating proper burner operation, switch means actuated by said electric means for rendering inoperative said charging circuit so that said discharge device will remain operative, a cut off circuit including said source of power, means connecting said cut off circuit to said discharge device, and further switch means actuated by said electric means for completing said cut off circuit only when said relay is deenergized and said switch means is in actuated position so that said dis-

charge device will be maintained inoperative upon a subsequent demand for burner operation by the control means.

3. In a control system for a fuel burner having a control means associated therewith for indicating the need for burner operation, in combination, an electron discharge device adapted to be energized by the control means, a relay having switch contacts for initiating operation of the burner, means connecting said relay in circuit with said discharge device, a condenser, means connecting said condenser in current controlling relation to said discharge device, a charging circuit connected to said condenser, 15 said charging circuit being operable to charge said condenser after a predetermined time delay following the operation of the control means so that said condenser will reduce the current flow in said discharge device below the point necessary to maintain said relay energized, electrically operable means having switch contacts and adapted to be energized by combustion responsive means, means including switch contacts actuated by said electrically operable means for 20 rendering said charging circuit ineffective, biasing means, circuit means connecting said biasing means to said discharge device, and means including switch contacts of said electrically operable means and switch contacts of said relay 25 for completing an electrical circuit from said biasing means to said discharge device to maintain said device inoperative when there has been no need for operation of the burner and said combustion responsive means is indicating the 30 presence of combustion and the control means subsequently indicates a need for burner operation.

4. Apparatus for controlling a fuel burner system having a fuel burner and a control means for indicating the need for operation of the burner, comprising in combination, a source of power, an electron discharge device, a relay, an electric circuit adapted to be completed by the control means for connecting said discharge device and said relay in an energizing circuit to said source of power, means actuated by said relay when energized for initiating operation of the burner, electric means adapted to be energized by combustion responsive means, first and second biasing circuit means, means including said electric means and said relay for connecting said first biasing circuit means in current controlling relation to said discharge device to render said device inoperative after a predetermined length of time when only said relay is operative, and means including said second biasing circuit means to maintain said device inoperative when said combustion responsive device is falsely indicating the presence of flame following a normal burner shutdown and the control means is subsequently actuated.

5. A control apparatus for a fuel burner system having a fuel burner and a control means for indicating the need for burner operation, comprising in combination, a source of power, an electron discharge device, a relay having "in" and "out" switch contacts, an electric circuit connecting said discharge device and said relay in an energizing circuit when said circuit is completed by means including the control means, means actuated by certain of the "in" contacts of said relay for initiating operation of the burner, combustion responsive means having "in" switch contacts actuated when a burner flame is present, first and second biasing means, first circuit means including the control means for connecting said

first biasing means to said discharge device in current controlling relation to render said device inoperative after a predetermined length of time, second circuit means including "in" contacts of said relay and said combustion responsive means for rendering said first biasing means ineffective when a burner flame is present, third circuit means including "in" contacts of said combustion responsive means and "out" contacts of said relay connecting said second biasing means to said discharge device to maintain said device inoperative when said combustion responsive means is operating falsely and there is a subsequent indication of a need for burner operation by the control means.

6. Control apparatus for a fuel burner system having a fuel burner and a control means for indicating the need for burner operation, comprising in combination, first and second electron discharge devices, first and second relays having a plurality of switch contacts, a source of power, a first electric circuit including said control means for connecting said first relay and said first discharge device to said source of power, switch means actuated by said first relay for initiating operation of the burner, a second electric circuit connecting said second relay and said second discharge device to said source of power, a burner flame responsive circuit, means connecting said circuit in current controlling relation to said second discharge device so that said discharge device will render operative said second relay on the presence of flame, first and second biasing means, circuit means connecting said first biasing means to said first discharge device when said first circuit is completed so that after a predetermined length of time said first discharge device will be rendered inoperative, a third electric circuit including switch means actuated by said first and second relays for short circuiting said first biasing means, and a fourth electric circuit including switch means actuated by said second relay connecting said second biasing means to said first discharge device to maintain said first discharge device inoperative when said flame responsive circuit is falsely maintaining said second discharge device operative and there is a subsequent indication of a need for burner operation by the control means.

7. Control apparatus for a fuel burner system having a fuel burner and a control means for indicating the need for burner operation, comprising in combination, an electron discharge device having an anode, cathode and control electrode, an alternating current source of power, a relay, a first electric circuit for connecting said relay and the anode-cathode circuit of said discharge device to said source of power so that said device is conductive on alternate half cycles of said source of power, switch means actuated by said relay for initiating operation of the burner, a condenser, means connecting said condenser between the control electrode and cathode of said discharge device, a source of charging current, time delay resistive means, a second electric circuit connecting said source of charging current through said time delay resistive means to said condenser so that said condenser is slowly charged to bias said discharge device below the point necessary to maintain said relay energized, combustion responsive means actuated on the presence of flame, means including said combustion responsive means when actuated for discharging said condenser to maintain said discharge device operative, a third electric circuit for effectively

connecting said source of power to the control electrode of said discharge device only when said combustion responsive device is actuated and said relay is deenergized, said third circuit having an alternating current phase opposite the phase of said first circuit.

8. In a safety control system for apparatus normally operable when energized to establish a predetermined condition, in combination, means including an electron discharge device having an input circuit and controlling said apparatus so that said apparatus is energized only when said discharge device is conductive, first means responsive to a condition indicative of the need for conduction of said device for operating said controlling means, means including a condenser in the input circuit of said device for controlling the conductivity of said device to cause the current flow to maintain a predetermined level for a predetermined time following a call for operation by said first responsive means, second means independent of said controlling means responsive to the establishment of said predetermined condition for shunting said condenser so as to maintain said discharge device conductive, and biasing means connected to said device for maintaining said device nonconducting when said first responsive means becomes operative indicating the need for operation of said control means and said second means is operating falsely.

9. Control apparatus for a fuel burner system having a fuel burner and a condition responsive means for indicating the need for burner operation, comprising in combination, means for initiating operation of the burner, control means for said initiating means including an electron discharge device having an input circuit and an output circuit, said control means being effective to operate said operation initiating means only when said discharge device is conductive, and means for controlling the conductivity of said discharge device, said last named means comprising said condition responsive means operable to complete an energizing circuit for said discharge device upon the need for operation of a burner, a first biasing circuit which is operable to deenergize said discharge device after a predetermined time when the burner fails to operate, a combustion responsive means which is operable to shunt out said first biasing circuit when said combustion responsive means and said responsive means are operative, and a second biasing circuit including said combustion responsive device connected to the input of said discharge device to maintain said discharge device inoperative only when said combustion responsive means is operating falsely and there is a subsequent demand for burner operation by the condition responsive means.

10. Control apparatus having means for controlling a fuel burner to establish combustion, comprising in combination, means including a normally conducting electron discharge device having a control electrode for initiating operation of the burner controlling means when said discharge device is conductive, and regulating means for controlling the conductivity of said discharge device, said regulating means including switch means for completing the conductive circuit of said discharge device upon need for operation of said burner controlling means to establish combustion, means responsive to establishment of combustion for maintaining said discharge device conductive when said apparatus is functioning properly, biasing means, and means including said

combustion responsive means connecting said biasing means to the control electrode of said discharge device for maintaining said device non-conductive when said combustion responsive means indicates establishment of combustion and when said switch means are not indicating need for operation of said burner controlling means to establish combustion.

11. In a safety control system for a fuel burner, an electron discharge device having an anode, a cathode and control electrode, a source of power, means connecting said anode and said cathode in energizing relation to said source, burner control relay means connected in said last named connection, means including combustion responsive means for maintaining said relay means operative upon the establishment of combustion, a biasing voltage, and means including said combustion responsive means for connecting said biasing voltage to said control electrode to apply a voltage thereto and prevent operation of said discharge device when said combustion responsive means is falsely indicating the presence of combustion.

12. Control apparatus for a fuel burner, comprising in combination, an electron discharge device having an anode, a cathode and control electrode, a source of power, means connecting said source of power in energizing relation to said anode and said cathode, relay means connected in said last named connection adapted when energized to initiate operation of the burner, a condenser timing circuit, means connecting said timing circuit in current flow controlling relationship to said discharge device, combustion responsive means for indicating proper operation of the burner, said combustion responsive means comprising a source of signal potential which is indicative of the presence or absence of combustion, means connecting said combustion responsive means to said timing circuit so that upon failure of said combustion responsive means to indicate the presence of combustion said timing circuit will be charged after a predetermined time delay by said signal potential to render said discharge device nonconductive and said relay means de-energized, and further means including said combustion responsive means for shunting said timing circuit when there is a flame at the burner.

13. Control apparatus for a fuel burner having control means for indicating the need for operation of the burner, the combination comprising, a source of power, an electron discharge device having an input and output circuit, a first control relay for initiating burner operation, means connecting said relay in the output circuit of said device, circuit means adapted to be completed by the control means for connecting said device in an energizing circuit to said source of power, biasing means, a timing condenser, a second control relay, means including said first relay when energized for connecting said second relay to said source, means including said second relay for connecting said biasing means to said condenser, means connecting said condenser to said input of said device for rendering said device inoperative after a predetermined time following the energization of the second relay, and further means for rendering said biasing means ineffective to charge said condenser when there is an indication of burner flame.

14. Control apparatus for a fuel burner having control means for indicating the need for operation of the burner, the combination comprising,

a source of power, an electron discharge device having an input and output circuit, a first control relay for initiating burner operation, means connecting said relay in the output circuit of said device, means adapted to be energized by the control means for connecting said device in an energizing circuit to said source of power, biasing means, a timing condenser, a second control relay, means including said first relay when energized for connecting said second relay to said source, means including said second relay for connecting said biasing means to said condenser, means connecting said condenser to said input of said device for rendering said device inoperative after a predetermined time following the energization of said second relay, and further means for rendering said biasing means ineffective to charge said condenser when there is an indication of burner flame and to render inoperative said second relay means.

15. Control apparatus for a fuel burner having control means for indicating the need for burner operation, the combination comprising, a source of power, an electron discharge device, a control relay for initiating burner operation connected in circuit with said device, means adapted to be energized by the control means for connecting said device and said relay in an energizing circuit to said source, energizable means for indicating proper burner operation, first biasing circuit means including said burner operation indicating means for rendering inoperative said device after a predetermined time delay upon a failure of burner operation, a reset switch associated with said first biasing circuit means for rendering said device and relay operative to attempt to initiate a further burner operation, and second biasing circuit means for rendering said device inoperative upon said indicating means operating falsely, said reset switch being ineffective to initiate operation of said device when said indicating means is operating falsely.

16. Control apparatus for a fuel burner having control means for indicating the need for operation of the burner, the combination comprising, a source of power, an electron discharge device having an input and output circuit, a first control relay for initiating burner operation, means connecting said relay in the output circuit of said device, means adapted to be energized by the control means for connecting said device in an energizing circuit to said source of power, biasing means, a timing condenser, a second control relay, means including said first relay when energized for connecting said second relay to said source, means including said second relay for connecting said biasing means to said condenser, means connecting said condenser to said input of said device for rendering said device inoperative after a predetermined time following the energization of said second relay, a reset switch for shunting said timing condenser to initiate operation of said device following de-energization of said device by said timing condenser, means responsive to proper burner operation for rendering said second relay inoperative and for shunting said input, and means including said second relay for rendering said reset switch ineffective when said burner operation responsive means is operating falsely.

17. Control apparatus for a fuel burner having control means for indicating the need for operation of the burner, the combination comprising, a first electrical switching means adapted to be energized by the control means, an elec-

tron discharge device, a source of power, a second electrical switching means, means including said first switching means when energized for connecting said device and said second switching means in an energizing circuit to said source, means actuated by said second switching means when energized for energizing the burner, a third electrical switching means adapted to be energized upon proper operation of the burner, first and second biasing circuit means, means including said third switching means and said second switching means for connecting said first biasing circuit means in current controlling relation to said discharge device to render said device inoperative after a predetermined length of time when only said first and second switching means are operative and said third is inoperative, and means including said second biasing circuit means to maintain said device inoperative when said third switching means is falsely indicating proper burner operation, said first switching means is energized and said second switching means is deenergized.

18. Control apparatus for a fuel burner having control means for indicating the need for operation of the burner, the combination comprising, a first electrical switching means adapted to be energized by the control means, an electron discharge device, a source of power, a second electrical switching means, means including said first switching means when energized for
